UNITED STATES PATENT OFFICE.

DAVID KARGER, OF MILWAUKEE, WISCONSIN.

CAP.

Application filed July 14, 1927. Serial No. 205,712.

This invention relates to caps and is particularly concerned with a combination leather and knit cap.

Leather caps have certain desirable qualities, such as shape-retention, durability and warmth, particularly against winds, but they also have certain undesirable qualities in that they require special means for ventilation and in that they do not lend themselves to constructions in which stretching is necessary or desirable.

It is the purpose of my invention to construct a cap in part of leather and in part of knitted material, so as to retain the desirable features of both for their respective purposes, and to do so by an arrangement of parts whereby ventilation is properly taken care of and manufacture, practically and at low cost, is enabled.

20 In the accompanying drawings:—

Fig. 1 is a front view of a cap constructed in accordance with my invention;

Fig. 2 is a side view, with the crown partly broken away;

25 Fig. 3 is a section through the cap taken transversely thereof on the line 3—3 of Figure 2;

Fig. 4 is an enlarged fragmentary vertical section taken substantially on line 4—4 of 30 Fig. 2;

Fig. 5 is an enlarged fragmentary section taken substantially on line 5—5 of Fig. 2;

Fig. 6 is a front view showing a modified form of cap embodying my invention; and

35 Fig. 7 is a side view of the cap illustrated in Fig. 6.

The cap includes an outer crown 1 formed of two or more suitably shaped pieces of leather sewed together, as shown.

40 Within the outer crown 1 I provide an inner crown 2 which is knitted of wool yarn and is preferably of open rib knit formation. This inner crown, adapted to fit the wearer's head snugly, possesses very appreciable elasticity and is knitted appreciably smaller than the outer crown 1 so as to leave a space 3 between it and the outer crown. The drawings have been somewhat exaggerated here to make the point clear.

45 50 When the cap is placed upon the wearer's head the inner crown is stretched slightly, so as to be placed under tension, and due to its elasticity, fits snugly about the head holding the outer crown, supported from its margin, and relatively non-elastic self-supporting inherently, in position compara-

tively loosely upon the head. Thus a properly fitting cap and desirable air circulation between the leather outer crown and the head of the wearer is effectively provided 60 for.

The wool from which the inner crown is knit is preferably of long fibre wool and the fibres thereof are of sufficient length to provide, on the inner face of the fitting crown, 65 a nap 4, of such depth or thickness as to enhance air circulation, particularly in conjunction with the interstices resulting from the stretching of the knitted crown upon the head. The nap fibres preferably 70 extend downwardly, as indicated in Figure 4, for a purpose which will appear presently.

In securing the inner crown to the outer crown, the former is disposed with its outer 75 margin flat against the inner margin of the outer crown, after which these margins are secured together by a single row of stitching 5. Also, a whipping or overcasting 6 is provided, which serves, among other purposes to be pointed out presently, to assist in compressing the joined margins of the crown, as shown, the margin of the inner crown, as indicated at 7, 8 being preferably 80 slightly enlarged so as not to draw the 85 margins against the head. When the cap is drawn downwardly about the head, the fibres of the nap 4 are turned upwardly so as to be bent back upon themselves, as indicated in Fig. 5, so, in effect, as to assist in 90 keeping the main body of the inner crown slightly away from the head, notwithstanding its snug fit. The outer crown, supported from the margin of the inner crown, 95 covers the head relatively loosely, as will now be clear. This permits ready circulation without interfering with the efficiency of the cap as a protection against cold winds.

The cap of my invention also has means, 100 capable of being turned into and out of use, for protecting the back of the neck and the ears of the wearer, such means being adapted to be secured under the chin of the wearer to hold them firmly in place and for further 105 warmth. Such means are not well adapted for construction of leather, since it does not lend itself well to stretching, and I therefore construct them of knitted material.

Secured to the joined margins of the 110 crowns, by means of stitching 6, which serves also as over-casting for the margins,

is a neck band 9, extending around the back and side portions of the crowns, this neck band terminating at each end in a flap 11, formed by rack knitting. In the form of 5 cap shown in Figures 1 and 2, the flaps 11 are made by rack knitting in two directions, to effect tapered flaps with axes at right angles to the base of the flap, whereas, in the form shown in Figures 6 and 7, the flaps 10 11' are rack knitted in one direction to effect a tab form of flap extending forwardly at an obtuse angle. Formation of these flaps or tabs by rack-knitting is important both from the standpoint of manufacture and result. In manufacture, the bands are knitted 15 on a flap knitting machine having a rack lever which may be brought into play at the proper point to rack the needles with the result in form pointed out without raw or 20 ragged edges. Furthermore, the resulting flap lends itself to stretching lengthwise, by which their ends may effectively be brought together under the chin of the wearer, the knitting closing up, under such stretching, 25 to effect better protection for the ears and chin of the wearer. These flaps also possess very appreciable elasticity and act to hold the non-elastic leather crown 1 securely in 30 position.

30 The nature of the stitching 6 is such as to effect a hinging connection. The neck band with its terminating flaps or tabs may thus be made to occupy two positions. In their upper position, i. e. out of use, they are held 35 up by suitable buttons 12, on the outer crown, as shown in Figures 1 and 2 and Figures 6 and 7. One of the flaps is also provided with a button (not shown) on the inside thereof, for co-operation with the button hole at the end of the other flap, whereby 40 the same may, when swung down, be joined together under the chin of the wearer.

A knitted front band 10 is also secured to the front and side portions of the outer 45 crown, the lower edge of this band being secured to the joined margins of the crowns by continuation of the stitching 6.

It is to be noted that when the band and flaps are down, as would be the case in 50 especially cold weather, the margin of the outer leather crown is drawn close to the head for a considerable portion of the perimeter of the cap margin and, while ventilation is not closed off entirely, it is 55 effectively reduced to some extent for the time being.

While I have referred to the outer crown of my cap as being constructed of leather, it will be obvious, of course, that such ma-

terials as leatherette or leatheroid may be 60 employed as effective substitutes and my appended claims are intended for interpretation accordingly. It will also be evident that gores of other material may be inserted 65 if desired without departing from the scope and spirit of the appended claims.

I claim:

1. In a cap, a relatively loose fitting approximately hemi-spherical outer crown of 70 impervious material, a relatively tight fitting approximately hemi-spherical inner crown of knitted material, the margin of the latter being slightly enlarged, said crowns being joined together at their margins.

2. In a cap, a relatively loose fitting outer 75 crown of leather, and a relatively tight fitting inner crown of knitted material spaced away from the outer crown, said crowns being joined together at their margins, and the inner crown projecting 80 inwardly beyond the cap margin and being provided at its inner face with means acting to space it away from the wearer's head and permitting flow of air therebetween and 85 said inner crown.

3. In a cap, a relatively loose fitting outer 90 crown of leather, and a relatively tight fitting inner crown of knitted material spaced away from the outer crown, said crowns being joined together at their 95 margins and the marginal portion of the inner crown being compressed, said inner crown projecting inwardly beyond the cap margin above and adjacent said compressed portion, the inner crown being provided on its inner face with a nap of appreciable depth and open formation adapted to support the inner crown in spaced relation to the wearer's head and to permit circulation 100 of air through the space between the wearer's head and said inner crown.

4. In a cap, a relatively loose fitting outer 105 crown of leather, and a relatively tight fitting inner crown of knitted material spaced away from the outer crown, said crown being joined together at their margins, and the marginal portion of the inner crown being compressed, said inner crown projecting inwardly beyond the cap margin above and adjacent said compressed portion, and being provided on its inner face with a nap of appreciable depth, the fibres of which are directed downwardly toward the margin of 110 the cap.

In witness whereof, I hereunto subscribe 115 my name this 11th day of July, 1927.

DAVID KARGER.
